CARBURETOR

Charles R. Snyder, Miami Beach, Fla.

Application November 16, 1946, Serial No. 710,388

6 Claims. (Cl. 261—50)

1

This invention relates to improvements in carburetors for internal combustion engines, it being a general object of the invention to provide a carburetor so constructed as to produce in its operation properly proportioned combustible mixtures of volatized liquid fuel and air, and wherein such mixtures are delivered in regulated quantities to the cylinders of an associated engine in a manner best suitable to obtain high efficiencies in the operation of the engine.

In conventional carburetor construction, liquid motor fuel is supplied to one or more vertical jets, or liquid fuel-receiving wells, under control of a float valve in a fuel reservoir. The fuel is withdrawn from these jets or wells by the air stream passing through the mixing chamber of the carburetor under the action of the piston of an associated engine. Normally, there is provided a manually operated throttle valve in the outlet of the carburetor mixing chamber to govern the flow of fuel mixture to the engine cylinders. In such conventional carburetors, their construction is such that the motor fuel is not efficiently commingled with atmospheric air drawn into the carburetor, that is, the liquid fuel is not effectively vaporized or mechanically reduced to fine particles for intimate admixture and union with atmospheric oxygen to obtain an explosive mixture from which maximum engine power may be developed with the least amount of fuel wastage.

It has been observed that in the operation of such a carburetor, the liquid fuel drawn into the mixing chamber is so incompletely vaporized that it commonly collects in liquid films on the surface of the air throttle valve, the latter functioning as a baffle or turbulence-promoting element. The unvaporized fuel is removed from the surfaces and peripheral edges of the throttle valve by the sweep of air thereover and in particle sizes too large for instantaneous and complete vaporization. For this reason, intake manifolds and passages have been developed having physical designs for increasing turbulence in the mixture flowing to the engine cylinders, together with various types of heaters for assisting in the vaporization of the liquid fuel before final delivery thereof to such cylinders.

In addition to incomplete fuel vaporization, and its resultant fuel wastage and other disadvantages, conventional carburetors are provided usually with a manually operated air valve control which admits of mixed fuel delivery to engine cylinders in a manner inconsistent with the fuel demands required in various stages of

2

engine operation. For instance, when an engine is laboring under heavy load conditions, or when the accelerator control of the carburetor is substantially fully depressed, as in passing vehicles proceeding in the same direction, or in other attempts to produce rapid increase in the speed of a motor vehicle, the substantially fully open position of the air throttle valve of a standard carburetor, under these conditions, cause the carburetor to supply the engine cylinders with fuel mixtures in which the fuel-air ratio and volume of the mixture are disproportionate to the proper working requirements of the engine.

Accordingly, the present invention has for certain of its objects, among others, to provide: a carburetor in which the volumes of the mixed fuel delivered thereby to the engine cylinders, and the fuel-air ratio of the mixtures, are governed automatically by working loads on the engine in addition to the control provided through the operation of manually regulated valves; a carburetor in which float-actuated valve controls are eliminated; a carburetor in which the air throttle valve is located in the entrance to the fuel-mixing chamber of the carburetor; a carburetor having a movable control valve for regulating the metered inflow of liquid fuel into a passage leading into the mixing chamber, and wherein provision is made for advancing a confined and independent stream of air through the passage to produce a primary fuel-air mixture which is forced through spray ports and delivered in an atomized state into the main air stream of the carburetor, producing the final fuel mixture; a carburetor in which a fuel-metering valve and air-throttle valve are linked together for movement in unison for maintaining proper proportions in the fuel-air mixture; a carburetor having a check mechanism responsive to varying degrees of vacuum in the mixing chamber thereof for restraining automatically the fuel-metering and air-throttle valves against operational movement under abnormal conditions of operation, and for releasing said valves upon restoration of normal operating conditions; and in the provision of a carburetor which will function in any position of operation so that the same may be adapted for use in conjunction with airplane engines.

Another object of the invention is to provide a carburetor which is characterized by its mechanical simplicity, manufacturing economy and the elimination of delicate controls and parts readily susceptible to mechanical disorders.

This application constitutes a continuation-in-part of my prior application, Serial No. 670,814, filed May 18, 1946.

For a further understanding of the invention, reference is to be had to the following description and the accompanying drawings, wherein:

Fig. 1 is a vertical transverse sectional view taken through a carburetor constructed in accordance with the present invention;

Fig. 2 is a top plan view thereof;

Fig. 3 is a vertical sectional view on the plane indicated by the line 3—3 of Fig. 1;

Fig. 4 is a fragmentary enlarged vertical sectional view taken through the fuel metering valve assembly of my improved carburetor;

Fig. 5 is a detail horizontal sectional view on the plane indicated by the line 5—5 of Fig. 4;

Fig. 6 is a vertical transverse sectional view on the line 6—6 of Fig. 4;

Fig. 7 is a front elevational view of the carburetor and disclosing the air-admitting valve shaft of the carburetor and its associated pneumatic check mechanism;

Fig. 8 is a rear elevational view of the carburetor disclosing the linkage uniting the operating shafts of the fuel-metering valve and the air-admitting valve;

Fig. 9 is a detail vertical sectional view taken through the pneumatic check mechanism for regulating the operation of the air-admitting valve shaft;

Fig. 10 is a detail elevational view of a portion of the air and fuel valve uniting linkage, as indicated by the line 10—10 of Fig. 8;

Fig. 11 is a horizontal sectional view on the line 11—11 of Fig. 10.

Referring more particularly to the drawings, wherein is illustrated a single preferred embodiment of my improved carburetor, the numeral 15 designates the lower section of the casing C of the carburetor and the numeral 16, the upper section thereof. The upper part of the lower section is formed with an outturned flange 17 upon the upper surface of which is seated a laterally directed annular flange 18 formed with the lower end of the upper section 16. These flanges are formed with registering openings 19, the openings in the flange 17 being threaded for the reception of the threaded shanks of cap screws 20, whereby to unite the two sections of the casing in assembled order. If desired, the lower part of the upper section may be formed with a depending web 21, which protects the joints formed between the meeting surfaces of the casing sections 15 and 16 against undesired fluid passage or seepage.

Clamped between the casing sections 15 and 16, when the same are in assembled order, is a transversely and horizontally extending bar or cross member 22, the ends of the latter being formed with longitudinally projecting flanges 23 which are adapted to be received in recesses 24 provided in the upper surface of the lower section 15. In transverse cross section, as in Fig. 3, the bar 22 is semi-round, as at 25, the same being formed with a flat under surface 26, the outer surfaces of the bar being spaced from the inner surfaces of the casing section, as at 27, to provide for the free flow of air through the casing from the air inlet end 28 thereof in the top of the casing to the carburetor fuel mixture outlet 29 in the bottom thereof.

The bar 22 is formed with a longitudinally extending bore 30 in which is stationarily positioned a tube 31. At one end, the tube 31 terminates in an externally threaded extension 32

projecting stationarily from the outer periphery of the flange 17 of the base section 15. The outer end of the extension 32 is formed with a seat with which engages the conically tapering end of a head 33 formed on a conducting pipe 34 through which liquid fuel, obtained from any suitable source of supply, is advanced positively, as under gravity or pump-pressure flow, to the carburetor. The head 33 is held in engagement with the seat of the extension 32 by means of an internally threaded nut 35, one end of the latter being flanged to engage with the shoulder formed at the back of the head 33, whereby to retain the head in its seated position in connection with the extension 32.

The tube 31, centrally of its length, is formed with vertical ports 35' which register with a corresponding vertical opening 36 formed in the bar 22. The upper end of this opening is enlarged to receive the lower end of an air-conducting tube 37, the upper portion of this tube being received in and retained by openings formed in the wall of the upper casing section 16. The tube 31, as shown particularly in Fig. 3, is shaped and positioned so that it does not interfere mechanically with the operation of a disk-shaped air-admitting or throttle valve 38, employed in regulating the flow of atmospheric air into the carburetor through its air inlet 28. The open upper end of the tube 37 is positioned so that air will pass through said tube at all times independently of the operating positions of the valve 38. The lower end of the vertical opening 36, which passes centrally through the bar 22, is enlarged and threaded for the reception of an injector plug 39, the latter being provided with a plurality of ports 40 of relatively restricted diameter as compared with that of the opening 36 and through which ports liquid fuel under metered flow control and admixed with air is delivered to the mixing chamber M of the carburetor.

Governing the flow of liquid fuel from the pipe 34 and the tube 31, through port 35, opening 36 and plug 39, is a sliding valve stem 41, the latter being mounted for longitudinal sliding movement in the tube 31 of the bar 22. The inner end of the stem 41 is of tapered or needle-like form, as indicated at 42, and normally is disposed in registration with the ports 35. However, through means to be hereinafter described, the position of the tapered end of the valve stem may be varied, under manual control, to regulate the amount of fuel adapted for delivery to the mixing chamber, or to arrest such flow altogether. By reference to Fig. 5, it will be noted that the walls 55 of the port or ports 35 are, in horizontal section, deepened or enlarged in the horizontal plane thereof registering with the stem 41, so that the body of the stem, when in registration with said ports, will not interfere with the flow of air into the mixing chamber from the air-supplying tube 37. By maintaining this flow of air in a manner independent of the operating positions of the valve 38, a carefully metered flow of motor fuel into the tube 37 is obtainable in all stages of engine operation, irrespective of the varying degrees of vacuum in the instrument below the air-admitting valve 38.

To operate the fuel-admitting valve stem 41, the outer end of the latter is diametrically enlarged and threaded as at 43, the same being received in the internally threaded bore 44 of a sleeve 45. This sleeve, as shown in Fig. 6, is formed with laterally and outwardly projecting ribs 46 which are slidably but non-rotatably received in elongated slots 47 provided in the outer

end of a stationary valve cage 48, the inner end 49 of said cage being received in a socket 50 formed in the flange 17 of the lower casing section 15. Inwardly the cage 49 is formed to provide a transverse web 51 for the slideable reception of the valve stem 41, and engaging with one surface of this web is one end of a coil spring 52, the latter surrounding the stem 41 for a limited part of its length. The end of the spring 52 opposite to that engaged with the web 51 bears on a collar 53 fixed to or forming a part of the stem, the tendency of the spring being to force the stem forwardly together with its sleeve 45. This movement is controlled by the engagement of the end surfaces of the ribs 46 of the sleeve 45 with cam surfaces 54 formed on the outer face of the hub 55 of a lever arm 56, the lever arm being freely rockable on the circular outer portion of the cage 48.

The lower end of the lever arm 56 carries a block 57 having horizontal trunnions 58, the latter being received in openings formed in the lower end of the arm 56. The block 57 is formed with a bore for the slideable reception of a manually operated control rod 59 which, conveniently, may be operated through the usual manual controls of a motor vehicle, such, for example, as the accelerator pedal or a hand throttle control, not shown. Fixed to the rod 59 is a pair of spaced collars 60, and surrounding the rod 59 and in engagement with the outermost of these collars is one end of a coiled expansion spring 61, the other end of this spring being in contact with the block 57. The extent of oscillating movement of the arm 56 may be controlled by contact with one or the other of a pair of stop screws 62, the latter being adjustably mounted in brackets 63 stationarily carried in connection with the casing section 15.

Substantially midway of its length, the arm 56 is provided with an outwardly projecting stud 64 around which is adjustably clamped the bifurcated head 65 of a pair of crank rods 66. These rods, toward their outer ends, engage the under side of a block 67 provided upon the lower end of a substantially vertically disposed link rod 68, the rods 66 at their outer ends being provided with pivot blocks 69 between which the lower end portions of the link rod 68 are pivotally confined. It will be understood that, in effect, the lever arm 56 and the crank rods 66 move as a rigid unit. In Fig. 8 of the drawings, the lever arm is shown as occupying a position providing for full opening of the fuel valve 41 and the air throttle valve 38, as occurs when the foot accelerator pedal of a motor vehicle is fully depressed. When the accelerator pedal is released, the lever arm 56 engages with the stop screw 62 at the right of Fig. 8. When the lever arm is so positioned, the crank rods 66 and the link rod 68 occupy relatively elevated positions.

The upper portions of the link rod 68 have fixed thereto a pair of spaced but adjustable clamps 70 and 71, and slidably mounted on the link rod between these clamps is a collar 72. This collar is formed, as shown in Fig. 10, with a pair of outwardly directed horizontal studs 73 which pivotally support spaced sets of clamping links 74, these links being frictionally united with the outer end portions of a pair of crank rods 75 by means of clamping screws shown at 76. The inner ends of the rods 75 project from a split type hub 77 which is adjustably fixed on the outer end of the operating shaft 78 of the air valve 38. Through this arrangement, and under normal

conditions of operation, the air-admitting and fuel valves 38 and 41 operate in unison to admit of proportioned inflow of air and fuel into the mixing chamber of the carburetor. However, provision is made under special conditions for admitting of limited relative movement, as will be presently described, between said valves to satisfy emergency or abnormal fuel demand conditions on the part of the carburetor.

For example, as my improved carburetor is constructed, its operation is responsive to variable suction, vacuum or pressure conditions existing in the mixing chamber of the carburetor. These conditions, in turn, are governed by (a) the operating positions of the air throttle valve 38 in the air inlet of the carburetor, and (b) the load conditions on the associated engine, or (c) any combination of conditions (a) and (b). Thus, if the associated engine should be laboring under high-load conditions, as when a motor vehicle is ascending a steep grade, the usual tendency of the vehicle operator is to press on manual controls opening the throttle and fuel valves to a maximum extent. Such action in an ordinary carburetor normally results in the feeding of an excess and too rich a fuel mixture to the engine cylinders, but in the present invention, this is avoided by the provision of a mechanism for checking or restraining the opening of the throttle and fuel valves until the engine attains higher operating speeds and the air valve comes into control instead of motor load.

To this end, the throttle valve shaft 78 is journaled for rocking movement in bearings shown at 79 and 80, which are formed in the upper casing section 16. One end of the shaft 78 projects beyond the bearing 80 and has fixed thereon a U-shaped bracket 81 carrying adjustable stop screws 82. The inner ends of these screws are appropriately spaced for coaction with a stationary vertical web 83 formed exteriorly on the outer wall of the bearing 80, as in Fig. 2, whereby to positively but adjustably limit the extent of oscillation of the throttle valve shaft. Also, fixed on the same outer end of the throttle valve shaft as the bracket 81 is the split clamping hub 84 of a crank arm 85. Loosely mounted on the outer end of the shaft 78 around the hub 84 is the bifurcated end 86 of another crank arm 87. The crank arm 87 has fixed thereto a pin 88 which projects through an opening 89 provided in the crank arm 85. The lower end of the pin 88 carries a stop nut 90 with which is engaged the lower end of a coil spring 91, the upper end of the spring being engaged with the crank arm 85. Normally, the crank arms 85 and 87 move in unison during turning movement of the throttle valve shaft. However, under special conditions, the spring 91 will permit of limited turning movement of the throttle valve shaft and the arm 85 relative to the arm 87 when the latter is held against movement by a fluid actuated check mechanism 92 herein-after defined.

This check mechanism has been best illustrated in Figs. 7 and 9 of the drawings. Conveniently, the same may consist of a cylinder 93 stationarily supported in a substantially vertical position by the lower section 15 of the casing. Arranged for reciprocation within the cylinder is a piston 94 having a rod 95 which extends through a bearing in the cap 96 carried by the upper end of the cylinder, the cap being formed with an air port 97. The upper end of the rod 95 is formed with a bifurcated head 98 which pivotally receives, as at 99, the lower end of a link 100, the upper end of

this link being pivotally connected as at 101 with the outer end of the crank arm 87.

The lower end of the cylinder 93 has threaded therein a fitting 102 in which is arranged a spring pressed check valve 103 which, when seated, prevents the passage of air, or other fluid, from within the cylinder to the exterior thereof through the air inlet port 104, thus holding the piston 94, for example, against downward movement.

To render the operation of the check mechanism responsive automatically to variable vacuum conditions present in the carburetor, the upper section 16 of the casing immediately below the valve 38 and in vertical registration with its shaft, is formed with an opening for the reception of a threaded pipe fitting or union 105. As shown in Fig. 7, the pipe 106 extends from this fitting or union to a valve cylinder 107, which is threaded, as at 108, into the lower end of the main cylinder 93. One end of the cylinder 107 is formed with a restricted passage 109 which is adapted to be closed by a needle valve 110. This valve is carried by a hollow piston 111 slidably mounted in the cylinder 107, and the latter piston is forced forwardly to seat the valve 110 by a spring shown at 112. At one side of the tapered end of the needle valve 110, the cylinder 107 is provided with a fluid-exhausting port 113. Internally, near its lower end, the cylinder 93 is slotted, as at 117, to render the check mechanism ineffective when the engine is operating in a given high speed range.

When the carburetor is functioning normally without excessive load conditions on the engine, sufficient vacuum is created in the air passage formed in the upper section 16 of the carburetor to move the piston 111 against the opposition of the spring 112 so that the needle valve 110 occupies a position opening the passage 109. This permits the piston 94 to move freely in the cylinder 93, particularly in a downward direction, as the air or other fluid beneath the piston 94 readily passes through the passage 109 and the exhaust port 113. However, if the engine is laboring under heavy load conditions, with resulting decrease in value of the vacuum in the upper part of the carburetor casing, the spring 112 becomes effective to move the piston 111 and the needle valve 110 to a position obstructing the passage 109, thus acting in conjunction with the check valve 103 to arrest descent of the piston 94 in the cylinder 93, thereby locking the throttle and fuel valves against undue actuation so that an overly rich fuel mixture will not enter the engine cylinders.

With the fuel-metering valve 41 and the air throttle valve 38 thus held against movement, if the vehicle operator actuates the carburetor manual control to its fullest extent in a direction to open the carburetor for maximum engine speed, the movement of the control rod 59 is absorbed by the spring 61, so that the latter becomes compressed and applies its load to the lever arm 56. As the engine gains speed, as a result of decreased load conditions thereon, the suction forces or vacuum in the carburetor casing increase, thereby moving the check mechanism piston 94 against the action of its spring to cause the needle valve 110 to open the passage 109, allowing the descent of the piston 94 under the forces exercised by the loading of the spring 61, thus restoring the carburetor and its controls to normal operation.

When the check mechanism is operative to

resist rotation of the throttle valve shaft 78, the controls of the carburetor are such that limited oscillation of the lever arm 56 may be provided to open the fuel metering valve to a limited degree. Thus in Fig. 8, it will be observed that the clamps 70 and 71 may be adjusted on the vertical link 68 in slightly spaced relation from the collar 72, so that the lever arm 56 may swing a distance in a direction to open the fuel-admitting valve 41 governed by the spacing between the clamp 70 and the collar 72. This adjustment provides for a slight increase in the richness of the mixture when the air throttle valve is held in substantially its position of closure by the operation of the check mechanism. Similarly, the spring 91 may be adjusted to admit of a limited amount of opening movement of the throttle valve 38 when the check mechanism is locked against movement of its piston 94, so that both the throttle valve and fuel valve may be opened to a limited extent with the piston 94 maintained against movement. The bearing 79 in the upper part of the carburetor casing is surrounded by a coil spring, shown at 114. One end of this spring is fastened to a collar 115 which is fixed on the throttle valve shaft 78, while the other end of the spring is fastened to the carburetor casing. This torsion spring tends to turn the shaft 78 in a direction maintaining contact between the collar 72 and the lower of the stop clamps 71.

By the provision of the air tube 37, a positive flow of air takes place therethrough to maintain the flow of primary fuel mixture into the carburetor mixing chamber at all engine speeds and vacuum or suction conditions existing in the carburetor casing. When the air throttle valve is substantially closed, causing static vacuum conditions around the injector plug 39, barometric pressures force atmospheric air through the tube 37 and around the valve stem 41. With the throttle valve open and motor load limiting the speeding up of the motor, dynamic vacuum still maintains suction at the injector to cause air flow through the tube.

The ports 40 in the injector plug 39 collectively possess less area than that afforded by the internal diameter of the tube 37 or the openings 36, with the result that the primary fuel mixture, upon being forcibly discharged from the nozzle plug into the mixing chamber of the carburetor, is in a finely divided or mist-like form, being propelled at high velocity into the air stream passing through the carburetor; and with which the primary mixture is combined to form the final combustible mixture for engine operation, thus overcoming variable vacuum conditions in the mixing chamber and preventing such conditions from interfering with the metering of fuel into the mixing passage 36. As the air throttle valve is opened to a greater extent, providing for increased air flow through the carburetor, dynamic vacuum conditions exist around the injector plug 39 to produce positively the desired force flow of air through the tube 37.

Conveniently, the upper end of the tube 37 may be associated with a conventional air filter, not shown, now commonly used on engine carburetors, so that air passing through the tube 37 will be filtered and solids apt to clog the ports 40 removed therefrom. By the position and formation of the bar 22 and the location of the plug 39 on the under side thereof, a conical vacuum region, as indicated by the arrows V, is believed to be maintained around the injector plug, so that the finely divided primary mixture issuing

from the ports of the plug will be first directed into a vacuum space before commingling actively with the air stream passing through the carburetor.

If desired, the interior of the lower section 15 of the carburetor casing may be formed with an abutment as indicated at 116. This abutment may be larger or smaller than indicated in the drawings, and if used, its purpose is to permit added turbulence of the air stream in the vicinity of the injector plug to insure complete commingling of the volatilized fuel particles with the air stream.

In view of the foregoing, it will be evident that the present invention provides a carburetor which is responsive automatically to the load on an associated engine to regulate the amount of the combustible fuel mixture supplied by the carburetor to the engine cylinders. By providing the cylinders at all times with a properly balanced fuel mixture, improved engine operating conditions under all stages of operation are made possible and, in addition, substantial savings are obtained, with respect to conventional carburetors, in fuel consumption. The mechanical construction of my improved carburetor is essentially simple, so that the same is reliable in operation, economical to manufacture, and is capable of giving long and satisfactory service without requiring frequent repairs or adjustments. While I have set forth above in considerable detail my beliefs as to the operating principles and theories which I consider to be inherent in my improved carburetor, nevertheless, I do not wish to be understood as being limited thereto, as the same are offered by way of explanation and to facilitate description and, of course, do not affect the mechanical performance of the carburetor as disclosed.

The construction of my improved carburetor is such that it may be used in virtually any operating position and, therefore, adapts itself readily to employment in airplanes. Also, the fact that the fuel is substantially fully vaporized in the mixing chamber, and the air throttle valve is located in the air inlet to the mixing chamber, internal icing conditions in the carburetor under low temperature operation is avoided. In the conventional carburetor, a large part of the fuel is vaporized from the surfaces of the throttle valve disposed on the engine side of the mixing chamber, that is, in or near the outlet of such a chamber. When so disposed, fuel evaporation from the surfaces of such a conventionally located throttle valve very often results in ice developing within the carburetor of a nature which interferes with proper operation of the throttle valve. These difficulties are eliminated by my present design.

Also, it will be understood that various changes may be made in the mechanical design of the carburetor without departing necessarily from the spirit and scope of the following claims.

I claim:

1. In a carburetor of the type having a casing formed with an induction conduit in which a movable air-control valve is positioned, there being an operating shaft for said valve mounted for rocking movement in the walls of said casing, together with means for imparting rocking movement to the shaft, the improvement comprising: a cylinder carried by said casing, a piston slidably in said cylinder, motion-transmitting means linking said piston with said rock shaft and providing normally movement of said piston in unison with said rock shaft, passage

means formed in said cylinder on one side of said piston, said passage means including an atmospheric vent, automatic valve means responsive to normal engine-created pressures existing in said conduit to maintain said vent open to the atmosphere and upon predetermined pressures in said conduit caused by the associated engine operating under a heavy load to close said vent and thereby retain said piston against movement in said cylinder.

2. A carburetor as specified in claim 1 comprising: air inlet and outlet port means of restricted cross-sectional area formed in the opposite ends of said cylinder, and a check valve positioned in the port means at the end of said cylinder carrying the automatic valve means.

3. In a carburetor of the type having a casing formed with an induction conduit, an air-flow control valve positioned in the conduit, an operating shaft for the valve mounted for rocking movement in the walls of the casing, and means for imparting rocking movement to the shaft to control the operating positions of the valve, the improvement comprising: a cylinder and piston assembly having a movable element, a crank arm fixed to one end of said valve shaft, a second crank arm loosely mounted on said shaft and disposed normally in side by side relationship with said fixed arm, yieldable connecting means uniting said crank arms for movement in unison with each other, motion-transmitting means linking the second or free crank arm with the movable element of said assembly, and means responsive to predetermined engine-developed suction forces established in said carburetor to apply motion-restraining forces to said piston, whereby to hold said air-flow control valve against operation except for limited movement on the part of said valve permitted by said yieldable connecting means for said arms.

4. In a carburetor for internal combustion engines, a casing formed with an internal longitudinally extending open-ended induction conduit, an air-flow control valve positioned in the conduit, an operating shaft for the valve mounted for rocking movement in opposite walls of the casing, the ends of said shaft projecting beyond said walls, a stationary cross member extending from one side to the other and disposed transversely of said conduit intermediately of its length, said member being formed with a passage which communicates at one end with a source of liquid fuel supply and at its other end with the interior of said conduit, a fuel-metering valve in said cross member controlling the flow of fuel through said passage, said fuel-metering valve at one end thereof extending exteriorly of said casing, crank arms carried by adjoining exterior ends of said rock shaft and said fuel-metering valve, manually operated means joined with the crank arm of said fuel-metering valve for imparting movement thereto, link means including a lost-motion connection uniting the crank arms of said rock shaft and fuel-metering valve, said lost-motion connection permitting of limited relative and independent movement of said fuel-metering valve with respect to said rock shaft and its air-flow control valve, check mechanism responsive to predetermined vacuum conditions existing in said conduit for restraining said valves against undue movement, and a yieldable element disposed in said mechanism providing for restricted movements of the air-flow control valve and said fuel-

metering valve against the restraint offered thereon by said check mechanism.

5. An engine carburetor of the type having a casing formed with an induction conduit, there being an air-flow control valve positioned in said conduit having a manually controlled operating shaft mounted for rocking movement in the walls of the casing, the improvements comprising: automatic check mechanism restraining said shaft against undue rocking movement upon the presence of predetermined negative pressure conditions in said induction conduit, said mechanism including a cylinder, a piston slidable in said cylinder, motion-transmitting means linking said piston with said rock shaft to produce normally movement of said piston in unison with said rock shaft, valve means responsive to said predetermined negative pressure conditions of said conduit to operatively retain said piston and shaft against normal movement, yieldable elements cooperative with said motion-transmitting means providing limited movement of said air-flow control valve when said piston is retained against movement by said check mechanism, passage means for delivering a volatile liquid fuel to said conduit for admixture with air passing therethrough, said fuel-delivering means including a fuel-metering valve, means linking the air-flow control valve and said fuel-metering valve for substantially synchronous movement, a lost-motion device in said last-named linking device providing for limited actuation of said fuel-metering valve before motion is imparted to said air-flow control valve, and manually controlled spring means for operating said valves.

6. In a carburetor for internal combustion engines, a casing formed with an internal longitudinally extending open-ended induction conduit, an air-flow control valve positioned in the conduit, an operating shaft for the valve mounted for rocking movement in openings formed in opposite walls of the casing, the ends of said shaft projecting beyond said walls, a stationary cross member extending from one side to the other and disposed transversely of

said conduit intermediately of its length, said member being formed with a passage communicating at one end with a source of liquid fuel supply and at its other with the interior of said conduit on the under side of said cross member, a fuel-metering valve disposed for longitudinal movement in said cross member controlling the flow of fuel through said passage and into said conduit, said fuel-metering valve at one end thereof extending exteriorly of said casing, a sleeve carried by the exteriorly extending end of said fuel-metering valve positioned for sliding movement in a casing-formed socket having slotted walls, said sleeve being formed with wings projecting laterally therefrom and slidably disposed in said slots, a crank arm rotatably mounted on the socketed portion of said casing, said crank arm having a hub formed with cam surfaces arranged in engagement with the wings of said sleeve, whereby upon oscillation of said crank arm sliding movement is imparted to said sleeve and said metering valve, and means linking said crank arm with the rock shaft of said air-flow control valve.
